CLAIM

The ornamental design for a motor tricycle, as shown and described.

DESCRIPTION

FIG. 1 is a top perspective view of a motor tricycle showing our new design;

FIG. 2 is a bottom perspective view thereof;

FIG. 3 is a front perspective view thereof;

FIG. 4 is a side elevation view of the right side thereof;

FIG. 5 is a side elevation view of the left side thereof;

FIG. 6 is a back perspective view thereof; and

FIG. 7 is an oblique view principally illustrating the left side thereof.

FIG.1.

FIG.2.

FIG.3.

FIG. 4.

FIG. 5.

FIG. 6.

FIG. 7.
